APARTMENT HOUSE SIGNALING AND
TELEPHONE SYSTEM

Charles Auth, Malba, Long Island, N. Y.

Application July 8, 1938, Serial No. 218,072

10 Claims. (Cl. 179—2)

This invention relates to selective electrical signaling and telephonic intercommunicating systems of a type particularly applicable for installation in apartment houses and the like, and such that a caller may signal any apartment from an entrance to the building and thereafter carry on a telephonic conversation with the occupant called.

Although systems of this general character are known, all previous systems of which I am aware, require the installation in each apartment in addition to the usual telephone set for carrying on conversation, of a sound producing signaling device, such as an electrically actuated bell, buzzer, chime, etc. for initially attracting the occupant's attention. This requirement of a separate signaling device in each apartment involves a considerable duplication of equipment, the initial expense of which is large, particularly where signaling devices of a more refined nature, such as chimes, are provided, as is found to be increasingly necessary in modern buildings to meet the present day demands of tenants. Also the installation of these more expensive signaling devices introduces additional items of expense inasmuch as pilfering is encountered where these devices are mounted in an exposed manner, whereas if the units are built-in to prevent this, especial and expensive precautions are required to assure proper tonal effects. Likewise with the more usual type of telephone set heretofore provided in such installations wherein the receiver is suspended from a cord, pilfering is also encountered, and such units are, moreover, unsightly.

In accordance with my invention I propose to eliminate this duplication of equipment, loss through pilfering and the unsightliness, by providing each apartment with only a transmitter and a loud speaker unit, both of which are preferably built-in, and by so associating all of the loud speaker units with one centrally located sound producing device and associated pick-up element, such as a chime and an associated carbon button transmitter, that any said loud speaker unit may be caused to reproduce the sound emitted by the sounding device or chime, in response to the usual push-button apartment selection made by the caller at the entrance to the apartment. The system is further so arranged that the occupant thus called may thereafter employ the transmitter and loud speaker unit for carrying on a two-way conversation with the caller, who has access to a telephone set at the entrance for this purpose.

The sounding device or chime and associated pick-up element or carbon button transmitter, may be mounted for example in the basement of the building, the pick-up device serving to convert the sounds emitted thereat into corresponding electrical oscillations for actuation of the loud speaker unit in the apartment selected by the caller. Connection of the pick-up device to a desired apartment loud speaker unit and actuation of the sounding device to call the occupant, is effected, under control of the caller, by a series of relays which are selectively actuated by depression of the apartment push buttons mounted at an entrance to the building, such as in the visitor's vestibule or at the tradesmen's entrance. Preferably also a switch is provided in each apartment, actuation of which serves to disconnect the signaling circuit aforesaid from the loud speaker and to connect the transmitter and loud speaker unit with the telephone set at the entrance to the building whereby the caller may converse with the apartment occupant.

As a further refinement, the system of my invention may be extended to employ several centrally located sounding devices each having a distinctively different sound, such as a bell, buzzer and a chime, each under control of a different series of apartment push-buttons disposed at various points about the building from which it is desired to originate calls, as in the visitor's vestibule, at the tradesmen's entrance, and in the superintendent's office, the different sounding devices thus selectively actuated serving thereby to indicate to the apartment occupant the source from whence the call originates. Where a system of this character is to be installed, the electrical circuits are of course appropriately modified, as will be explained, to assure that the proper sounding device will be caused to actuate the selected apartment loud speaker unit in accordance with the source from whence the call originated, and also to permit the apartment occupant called to converse telephonically with the party initiating the signal.

Referring now to the drawings for a more detailed explanation of the invention:

Fig. 1 is a diagrammatic representation, largely in the form of an electrical circuit diagram, of a preferred modification of the invention in accordance with that first referred to wherein a single sounding device is employed for actuating any desired apartment loud speaker unit in response to push-button selection; while

Fig. 2 is a similar diagrammatic representation of the more elaborate modification last referred

to wherein several distinctively different sound emitting devices are provided for indicating from which of several sources a call originates.

Referring to Fig. 1, the dashed rectangle A₁, A₂, A₃, represent different apartments, each of which in accordance with the invention is equipped with a transmitter T₁, T₂, T₃ and a loud speaker L₁, L₂, L₃, and also with a switch S₁, S₂, S₃. The rectangle V represents an entrance to the apartment, such as the visitor's vestibule, which is equipped with a telephone set including a transmitter T₄ and receiver R₄, and with a series of push-buttons P₁, P₂, P₃, one for each apartment, for initiating a call to any of the various apartments at the option of the caller. The dashed rectangle C represents a centrally located portion of the building, such as the basement, where a single sound producing element, in this case a chime S, is mounted together with an associated 10 pick-up element or transmitter T₅, and a series of relays R₁, R₂, R₃ and R₄ for connecting the pick-up element T₅ to the selected loud speaker unit L of the apartment selected and for thereafter actuating the sounding device S.

For an understanding of the circuit connections and operation of the system, assume that a caller in the vestibule V desires to call apartment A₁. To do this he momentarily depresses the corresponding push-button P₁ which closes a circuit from the positive terminal of a battery ! over conductor 2, through relay R₄ and the contacts of push-button P₁, the winding of relay R₁ and thence back to the negative terminal of battery ! over conductor 3. Closure of this circuit operates 15 relays R₁ and R₄, which thereafter release following release of the push-button. Operation of relay R₁ closes a circuit to energize the pick-up device T₅, this circuit being traced from the positive terminal of battery ! over conductor 2 through the middle front contact and armature of relay R₁, the primary winding of a transformer 4, through the pick-up device T₅, and back to the negative terminal of the battery over conductor 3. Operation of relay R₁ also closes a circuit connecting the secondary winding of transformer 4 to the loud speaker unit L₁ in apartment A₁, this circuit being traced from the lower terminal of this secondary winding over conductor 5, through the outer front contact and armature of relay R₁, over conductor 6, through the upper contact and movable arm of switch S₁, in apartment A₁, thence through the winding of the associated loud speaker L₁, and back to the secondary winding of transformer 4 over conductors 7 and 8. Closure 20 of the circuits above described thus prepares the loud speaker L₁ of apartment A₁ to reproduce any sounds emitted by the centrally located chime S. Operation of the chime is brought about by operation and release of relay R₄, which completes a circuit traced from the secondary winding of a transformer 10, energized from a source of alternating current 11, through the armature and front contact of relay R₄ and thence through the winding of a solenoid 12 for actuating the chime, and back to the secondary winding of transformer 10. The resulting energization of the solenoid 12 causes its armature 13 to be elevated and to strike against the upper sounding element 14 of the chime, the solenoid being immediately 25 thereafter released by release of relay R₄, causing the armature 13 to fall away and strike against the lower sounding element 15, whereupon the armature is returned to its normal position as shown by the resilient action of springs 16 on which the armature is supported in the manner

indicated. The sounds thus emitted by the chime are picked up by the transmitter T₅ and converted into corresponding electrical oscillations, which are relayed to the loud speaker unit L₁ over the circuits above traced, thereby causing these sounds to be reproduced by this loud speaker unit. 5

As explained above, relays R₁ and R₄ are operated for only a short interval, since their operating circuit above traced is opened upon release of push-button P₁. To assure that relay R₁ will be operated for a sufficient interval to transmit the sustained notes of the chime to loud speaker L₁ even though the push-button is depressed but momentarily, the release of this relay is retarded by condenser 9 which is connected through the inner front contact and armature of relay R₁ across the relay winding upon operation thereof. Preferably also relay R₄ is adjusted to operate slightly after relay R₁ operates, to assure that loud speaker L₁ is connected to pick-up device T₅, and this device energized, before the chime is actuated. 10 15 20

Battery ! may of course be substituted by a power pack, such as a dry rectifier, for supplying rectified direct current from the usual source of alternating current socket power. 25

A similar sequence of operations to that above described, would have occurred to actuate the loud speaker unit in either of apartments A₂ or A₃ had the corresponding push-buttons P₂ or P₃ been initially depressed by the caller, the only difference in operation being that in such case relay R₂ or R₃ would operate instead of relay R₁ to connect the pick-up transmitter T₅ to the loud speaker unit L₂ or L₃, actuation of such loud speaker thereafter being the same as that described for apartment A₁. 30 35

Reverting now to apartment A₁, loud speaker unit L₁ of which has been actuated by the chime as described, the occupant on being called will depress the push-button S₁ to connect the transmitter and loud speaker T₁, L₁ to the telephone set T'4, R'4, in the vestibule below for purposes of conversing with the caller, who of course for this purpose, removes the receiver R'4 from its switch hook. With the circuit as thus arranged, the transmitters T₁ and T'4 are energized from the battery !, the former over a circuit traced from the positive terminal of the battery over conductor 17, through transmitter T₁ and the lower contacts of switch S₁, back to the negative terminal of the battery, over conductor 18 and through the primary winding of induction coil 19 connected to receiver R₄; and the latter over a circuit traced from the positive battery terminal over conductor 20 and thence through intermediate contacts of switch S₁ and over conductor 21, through the primary winding of an induction coil 22 and transmitter T'4 to the negative battery terminal. Due to the fact that the energizing current for transmitter T₁ traverses the induction coil 19 connected to receiver R'4, and to the fact that transmitter T₄ is coupled through induction coil 22 to the loud speaker L₁ over conductors 7 and 21 and through contacts of switch S₁, the circuits are thus arranged for two-way conversation between the vestibule telephone set and that of apartment A₁. When the call as thus initiated is consummated, the caller returns the receiver R₄ to its switch hook, and the occupant of apartment A₁ releases switch S₁ whereby the circuit is restored to normal. Had the apartments A₂ or A₃ been called, the procedure for carrying on conversation with the caller would have been the 40 45 50 55 60 65 70 75 80 85 90 95 100

same except that the occupant of the apartment called would have operated switch S_2 or S_3 .

It will be understood of course that in Fig. 1 only three apartments A_1 , A_2 , A_3 and their associated signaling and telephone circuits have been shown merely for convenience, and that the system can be extended to embrace any number of apartments by merely providing additional equipment of the character described and multiplying the same in the manner shown.

Fig. 2 illustrates an extension of the system described in Fig. 1, to permit of initiating calls to the various apartments from any of several sources, such as from the visitor's vestibule, tradesmen's entrance, superintendent's office or from the immediate entrance to each apartment, and for producing a distinctively different sound on the loud speaker unit of the apartment called for each different source from which a call may be thus originated.

The apartments A_1 , A_2 , etc. are provided with loud speaker units, transmitters and switches L , T and S as in Fig. 1. Also the visitor's vestibule V is provided with the push-buttons P_1 , P_2 , etc. V and a telephone set R'_4 , T'_4 , as aforesaid. In addition a tradesmen's entrance H is provided at which the push-buttons P_7 , P_8 , etc. are multipled and which is also provided with a telephone set T_5 , R_5 . An apartment may be thus called from either the visitor's vestibule or from the tradesmen's entrance. Also the immediate entrances to the individual apartments A_1 , A_2 , etc. are provided with push-buttons P_{10} , P_{11} , etc., for signaling from these points. In addition the superintendent's office S is provided with a telephone set T_6 , R_6 and with a gang switch 30 , whereby the superintendent may communicate either with an apartment or with the visitor's vestibule.

40 The centrally located station C is in this case provided with three distinctively different sound producing devices, namely, a chime S , bell R and buzzer B , the chime being arranged to respond to calls initiated from the visitor's vestibule, the buzzer to calls originating at the tradesmen's entrance, and the bell to calls originating at the immediate entrances to apartments.

Each of the sound producing devices S , R and B , has associated therewith a pick-up element or transmitter T_5 , T_6 , T'_4 , for converting the sounds emitted by their associated sounding elements into corresponding electrical oscillations, which are relayed through a common transformer 4 to the loud speaker of the apartment called. 50 Connection of the appropriate pick-up element to the loud speaker called, and subsequent operation of the associated sound producing device, is under control of the relays R_1 , R_2 and R_7 , R_8 , R_9 which in turn are under control of the push-buttons P_1 , P_2 , etc., P_7 , P_8 , etc.; P_{10} , P_{11} , etc.

For an understanding of the circuits and operation of the system, assume that a call originates in the apartment vestibule, by depression of push-button P_1 to call apartment A_1 . Closure 60 of push-button P_1 completes a circuit for operation of relays R_1 and R_7 , this circuit being traced from the negative terminal of battery 1 over conductor 31 , through the winding of relay R_1 , thence over conductor 32 and through the contacts of push-button P_1 , thence over conductor 33 and through the winding of relay R_7 to the positive terminal of battery 1 over conductor 34 . These relays are thus operated for but a short interval and release again following release 70 of the push-button.

Operation of relay R_1 connects transmitter T_5 associated with chime S to battery 1 over a circuit traced from the negative battery terminal through the primary winding of transformer 4 , through transmitter T_5 , over conductor 35 , 5 through the middle front contact and armature of relay R_1 and back to the positive terminal of battery 1 , over conductors 36 and 34 . Operation of relay R_1 also completes a circuit from the secondary winding of transformer 4 to the 10 loud speaker unit selected, in this case L_1 , this circuit being traced from the upper secondary terminal over conductors 37 and 38 through the winding of speaker unit L_1 and the upper contacts of switch S_1 , thence over conductors 39 , 15 40 and 32 , and through the outer armature and front contact of relay R_1 , returning to the secondary winding of transformer 4 over conductor 42 . Relay R_7 is preferably designed to operate shortly after completion of the circuits thus 20 traced to energize the chime S over a circuit traced from one terminal of the alternating current source 11 , through the solenoid winding of the chime, and thence through the armature and front contact of relay R_7 , returning to the 25 opposite terminal of the source 11 . Energization of this chime causes the loud speaker unit L_1 to reproduce the sounds thereof by virtue of the pick-up action of the associated transmitter T_5 , the signals of which are relayed through the 30 winding of transformer 4 to the speaker unit over the circuits above traced.

The occupant of apartment A_1 upon being thus called to the phone, depresses switch S_1 , which disconnects at its upper contacts the circuit 35 through contacts of relay R_1 and connects, through its lower contacts, the apartment phone T_1 , L_1 with the vestibule phone T'_4 , R'_4 . The transmitters T_1 and T'_4 are thus energized over a circuit traced from the positive terminal 40 of battery 1 , over conductors 43 , 44 , 45 and 46 , through the lower left contacts of switch S_1 , where the current divides, a portion flowing through transmitter T_1 and thence through the lower right contacts of switch S_1 , over conductor 45 47 and contacts of the gang switch 30 , over conductor 48 and through the primary winding of induction coil 49 in the vestibule telephone set, to the lower terminal of transmitter T'_4 , where the current unites again with the remaining portion which flows from the point of division referred to at switch S_1 , over conductor 50 and through the primary winding of the vestibule telephone set induction coil 51 and over conductor 52 , through contacts of the gang switch 30 to 55 conductor 53 , and through the transmitter T'_4 , where the current through this transmitter units as aforesaid with that flowing through transmitter T_1 , the combined current thereafter returning to the negative side of the battery 1 , 60 over conductor 54 , through the lower contacts 55 of the tradesmen's telephone set, returning thence to the negative side of battery 1 , over conductor 56 . It will be observed that in the transmitter energizing circuits above traced, the current for the vestibule transmitter T'_4 flows through the primary of induction coil 51 , to the secondary of which the apartment loud speaker units are connected, over the circuit comprising conductors 38 and 50 and lower left contact of 70 switches S , so that when the vestibule transmitter is spoken into the corresponding sounds are reproduced by the apartment loud speaker L corresponding to the switch S which is actuated, in this case S_1 . Also it will be observed that the 75

energizing current for the apartment transmitter T_1 flows through the primary of induction coil 49 , so that when this transmitter is spoken into the corresponding sounds are reproduced by the 5 vestibule loud speaker R_4 connected to the secondary of induction coil 49 .

It will be understood of course that had the caller originally depressed push-button P_2 instead of P_1 , to initiate a call to apartment A_2 , the 10 operation of the system would be essentially the same as that above described with the exception that in this case relays R_2 and R_7 would have been operated at the centrally located station C to call apartment A_2 in the manner described 15 for apartment A_1 .

To assure that relay R_1 or R_2 as the case may be, remains operated for a sufficient interval to reproduce the sustained note of the chime by the 20 apartment speaker selected, irrespective of the rapidity with which the push-button P_1 or P_2 is released, the release of these relays is retarded by the condenser 41 , which upon actuation of either of these relays, is shunted across its winding over a circuit traced through its inner armature and front contact.

Should the call originate at the tradesmen's entrance H , depression of push-button P_7 or P_8 will operate relay R_1 or R_2 to connect the circuit of the pick-up device T_7 associated with the 30 buzzer B , with the apartment desired, and will also operate relay R_8 to actuate the buzzer to produce a corresponding signal at the apartment called. Assume for example that push-button P_7 is actuated. This completes a circuit to operate relays R_1 and R_8 , traced from the negative terminal of battery 1 , over conductor 31 and through the winding of relay R_1 , through the contacts of push-button P_7 to conductor 57 , thence through the winding of relay R_8 to the positive 40 side of battery 1 of the conductor 34 . The operation of relay R_1 completes the circuit above described for connecting the secondary winding of transformer 4 to the called apartment A_1 ; while the accompanying operation of relay R_8 45 completes a circuit through its outer armature and front contact from the voltage source 11 to actuate the buzzer B ; and also completes a circuit through its inner armature and front contact from the battery 1 to energize the pick-up transmitter T_7 , associated with the buzzer B , whereby the sounds produced by the buzzer are reproduced on the loud speaker at apartment A_1 .

When the apartment answers by depression of switch S_1 thereat, the tradesmen's telephone T_8 , 55 R_8 , upon removal of the receiver thereof from the switch hook, is connected to the apartment telephone for intercommunication. Thus the apartment transmitter T_1 and the tradesmen's transmitter T_5 are energized over a circuit traced 60 from the positive terminal of battery 1 , over conductors 43 , 44 , 45 and 46 , to the lower left contacts of switch S_1 , where the current divides, a portion flowing over conductor 50 , through the primary winding of induction coil 51 and through 65 transmitter T_5 , returning to the negative side of battery 1 over conductor 56 , and the remaining portion flowing from the point of division at switch S_1 , through transmitter T_1 , the lower right contacts of switch S_1 , over conductor 47 , 70 through contacts of the gang switch 30 to conductor 48 , thence over conductor 58 , through the upper right switch hook contacts 59 of the tradesmen's telephone set, and through the receiver R_8 , returning to the negative side of the battery over conductor 56 . It will be observed in the circuits 75

above traced that the current for transmitter T_5 flows through the primary of induction coil 51 connected to the apartment loud speaker units L_1 and L_2 , over conductors 33 and 50 , so that when the tradesmen's phone is spoken into the 5 loud speaker unit at the apartment called, namely L_1 , will be energized to reproduce the sounds thereof. Likewise the current for the apartment transmitter T_1 flows through the tradesmen's receiver unit R_8 , so that when transmitter T_1 is spoken into the sounds will be reproduced by the tradesmen's receiver, so that telephonic conversation between the parties may be carried on.

Should a caller wish to announce his presence at the immediate entrance to one of the apartments, he may do so by pressing push-button P_{10} or P_{11} at the apartment entrances respectively. This will energize relay R_1 or R_2 , as the case may be, at the centrally located station C and will also energize relay R_9 thereat, to actuate the bell R , and to connect its associated pick-up elements T_8 , through transformer 4 , to the loud speaker unit of the apartment corresponding to the push-button P_{10} or P_{11} which is actuated.

Assume for example that apartment push-button P_{10} is depressed. This completes a circuit to operate relays R_1 and R_9 , traced from the negative terminal of battery 1 , over conductor 31 , through the winding of relay R_1 , over conductors 32 and 48 , through the contacts of push-button P_{10} , 30 thence over conductor 60 , and through the winding of relay R_9 to the positive terminal of battery 1 over conductor 34 . Relays R_1 and R_9 will thus be energized, relay R_1 to complete, at its terminals, the circuit above traced for connecting 35 the secondary winding of transformer 4 to loud speaker unit L_1 of apartment A_1 . The operation of relay R_9 in turn connects, through its outer front contact and armature, the voltage source 11 to the bell R , thereby to energize the same; 40 and also connects through its inner front contact and armature, battery 1 to the pick-up device T_8 , whereby the sounds produced by the bell R are relayed by means of the pick-up device T_8 and the transformer 4 to the loud speaker unit of 45 apartment A_1 . Owing to the distinctive sound produced by the bell, the occupant knows that the caller is at the apartment door rather than in the vestibule or at the tradesmen's entrance, and responds accordingly.

The superintendent's phone T_6 , R_6 is arranged by means of the gang switch 30 for communication either with the vestibule phone $T'4$, $R'4$ or with any of the apartment phones. With the gang switch in its normal position as shown in 55 the drawings, the superintendent's phone is connected for communication with the vestibule phone.

For initiating a call from any apartment or from the vestibule to the superintendent's office, each apartment and the vestibule may be provided with a push-button circuit, closure of which operates a signal in the superintendent's office. This circuit is not shown as it is merely a standard form of circuit, consisting of a signaling device, such as a bell mounted in the superintendent's office and energized from source 11 upon closure of an apartment or vestibule push-button, the contacts of which for the various apartments and the vestibule, are wired in multiple, so that 60 closure of any one will complete the ringing circuit. It is not ordinarily required that the superintendent be enabled to signal the various apartments from his office, but should this be desired it would merely be necessary to provide his office 65 70 75 80 85 90 95

with a series of push-buttons corresponding to the apartments and to connect these push-buttons to circuits identical with those provided in the case of the vestibule and at the tradesmen's entrance, whereby the superintendent could produce a distinctive tone at the apartment called in the manner above described for the systems of the vestibule and tradesmen's entrance. The circuits whereby the superintendent could so signal the apartments have accordingly not been omitted in the interests of simplicity.

Assuming that the caller in the vestibule has signaled the superintendent's office, the superintendent responds by removing his receiver from the switch hook, thereby to connect his telephone set with the vestibule set. Thus the transmitters T_5 and T_6 will be energized over a circuit traced from the positive terminal of battery 1, over conductors 43, 44 and 45, where the current divides, a portion flowing to the receiver R_6 , through contacts of the gang switch and the right hand contacts on the switch hook and thence through other contacts of the gang switch and over conductor 61, through the primary winding of induction coil 51, over conductor 52 and through contacts of the gang switch to conductor 53, through transmitter $T'4$, returning to the negative side of the battery over conductor 54 normally closed contacts 55 at the switch hook of the tradesmen's phone and conductor 56; the remaining portion of the current in conductor 45 flowing through contacts of the gang switch, transmitter T_6 , and contacts of the associated switch hook to conductor 48, and through the primary winding of induction coil 49 to the negative side of transmitter $T'4$, returning therefrom to the negative side of battery 1 over the circuit above traced.

It will be thus observed that the energizing current for transmitter $T'4$ flows through the superintendent's receiver R_6 , so that when the vestibule phone is spoken into the sounds will be reproduced by the superintendent's receiver. Conversely the energizing current for the superintendent's transmitter T_6 flows through the primary winding of induction coil 49, so that when the superintendent's phone is spoken into corresponding sounds will be reproduced by the vestibule receiver $R'4$, which is connected to the secondary winding of induction coil 49.

With the gang switch 30 operated to the left, and with one of the apartment switches, such as S_1 , depressed, the superintendent's telephone set is connected to the corresponding apartment telephone set for intercommunication, over the following circuits. The transmitters T_1 and T_6 are energized over a circuit traced from the positive terminal of battery 1, over conductors 43, 44, 45 and 46 to switch S_1 , where the current divides, a portion flowing through the left hand lower contacts of switch S_1 , through transmitter T_1 and the lower right hand contacts of switch S_1 , over conductor 47 and through contacts of the gang switch 30 to conductor 62, thence through other contacts of the gang switch, through receiver R_6 , the right hand switch hook contacts of the superintendent's phone, through other contacts of the gang switch to conductor 63, and thence to the negative terminal of battery 1. Reverting to switch S_1 , the remaining portion of the current flowing over the circuit traced to conductor 46, from the positive terminal of battery 1, flows through the loud speaker L_1 and thence over conductor 38, through the secondary and primary windings of induction coil 51 to conductor 52,

and thence through the left hand contacts of the gang switch 30, and through switch hook contacts of the superintendent's telephone set to transmitter T_6 and through this transmitter and contacts of the gang switch 30 to conductor 63, 5 returning thus to the negative terminal of battery 1 as aforesaid.

It will be noted in the circuits above traced that the energizing current for the superintendent's transmitter T_6 flows through the loud speaker L_1 , and that conversely the energizing current for the apartment transmitter T_1 flows through the superintendent's receiver R_6 , so that when these transmitters are spoken into the sounds are reproduced on the appropriate receiver units for establishing two-way conversation between the superintendent's phone and that of the apartment.

I claim:

1. In a selective signaling system: a sound producing element, a pick-up device thereat for converting said sound into corresponding electrical oscillations, a plurality of sound reproducing elements, a plurality of relays individual thereto, connections from said pick-up device to each of said sound reproducing elements through contacts of its associated relay, switching means for selectively actuating any of said relays thereby to connect said pick-up device to the associated sound reproducing element, and means responsive to actuation of said switching means for actuating said sound producing element. 20

2. In a selective signaling system: a sound producing element, a pick-up device thereat for converting said sound into corresponding electrical oscillations, a plurality of sound reproducing elements, a plurality of relays individual thereto, connections from said pick-up device to each of said sound reproducing elements through contacts of its associated relay, switching means for selectively actuating any of said relays thereby to connect said pick-up device to the associated sound reproducing element, and means including an additional relay responsive to actuation of said switching means for actuating said sound producing element. 35

3. In a selective electrical signaling and communicating system: a sound producing element and associated pick-up device, a plurality of transmitting and receiving units, selective switching means and means controlled thereby for connecting said pick-up device to any of said receiving units, means responsive to actuation of said switching means for energizing said sound producing element, an additional transmitting and receiving unit at said switching means, and means including a switch at each of said plurality of transmitting and receiving units for establishing a two-way talking circuit between the associated transmitting and receiving unit 60 and said additional transmitting and receiving unit. 55

4. In a selective signaling system: a plurality of electrically actuated sound producing elements, each productive of a distinctively different sound; pick-up means thereat for converting said sounds into corresponding electrical oscillations; a plurality of sound reproducing elements; a plurality of sets of selective switching devices and means controlled thereby for connecting by appropriate actuation of a switching device in any said set, said pick-up means to any said sound reproducing element, and for actuating one of said sound producing elements, the particular sound producing element so actuated being determined 70 75

by the particular set containing the switching device so actuated.

5. In a selective signaling system: a plurality of sound reproducing elements; a plurality of electrically actuated sound producing elements, each productive of a distinctively different sound; pick-up means for converting said sounds into corresponding electrical oscillations; a like plurality of selective switching devices, and means controlled thereby for connecting by appropriate actuation of a switching device in any said set, said pick-up means to any said sound reproducing element, and for actuating one of said sound producing elements, a different such element responding to actuation of switching devices in each said set.

6. In a selective electrical signaling and communicating system: a plurality of electrically actuated sound producing elements each productive of a distinctively different sound; pick-up means for converting said sounds into corresponding electrical oscillations; a plurality of remotely located signal receiving stations each equipped with a transmitting and a receiving unit; means including a switch adjacent each said signal receiving station for connecting said pick-up means to said station and for actuating one of said sound producing elements to produce a corresponding sound at said station; a plurality of selecting stations remote from said signal receiving stations; means including a selective switching device at each of said selecting stations for connecting said pick-up means to any said signal receiving station and for actuating one of said sound producing elements, a different said sound producing element for each said selecting station; and means including a telephone set at each of said selecting stations and a switch at each of said signal receiving stations for establishing a two-way talking circuit between any said selecting station and the signal receiving station selected thereby.

7. In a selective electrical signaling and communicating system: a plurality of electrically actuated sound producing elements each productive of a distinctively different sound; pick-up means for converting said sounds into corresponding electrical oscillations; a plurality of remotely located signal receiving stations, each equipped with a transmitting and a receiving unit; means including a switch adjacent each said signal receiving station for connecting said pick-up means to said station and for actuating one of said sound producing elements to produce a corresponding sound at such station; a plurality of selecting stations remote from said signal receiving stations; means including a selective switching device at each of said selecting stations for connecting said pick-up means to any said signal receiving station and for actuating one of said sound producing elements, a different said sound producing element for each said selecting station; means including a telephone set at each

of said selecting stations, and a switch at each of said signal receiving stations for establishing a two-way talking circuit between any said selecting station and the signal receiving station selected thereby; an additional station equipped with a transmitting and receiving unit; and means including a switch thereat for establishing a two-way talking circuit between the transmitting and receiving unit at said station and the transmitting and receiving unit at any of said signal receiving stations and alternatively with the transmitting and receiving unit at at least one of said selecting stations.

8. In a selective signaling system: an electrically actuated sound producing element, a pick-up device thereat for converting said sounds into corresponding electrical oscillations, a plurality of sound reproducing elements, switching means and means controlled thereby for selectively connecting said pick-up device to any of said sound reproducing elements, means responsive to actuation of said switching means for actuating said sound producing element, and means independent of said switching means for maintaining the connection of said pick-up device to a sound reproducing element for an interval sufficient to permit the transmission of a sustained note from the sound producing to the sound reproducing element so connected.

9. In a selective signaling system: a sound producing element, a pick-up device thereat for converting said sound into corresponding electrical oscillations, a plurality of sound reproducing elements, a plurality of relays individual thereto, connections from said pick-up device to each of said sound reproducing elements through contacts of its associated relay, switching means for selectively actuating any of said relays thereby to connect said pick-up device to the associated sound reproducing element, means responsive to actuation of said switching means for actuating said sound producing element, and means including a condenser and contacts of said relays for maintaining the connection of said pick-up device to a sound reproducing element for an interval sufficient to permit of transmitting a sustained note from the sound producing to the sound reproducing element so connected.

10. In a selective calling system: a plurality of sound reproducing elements, a plurality of switches individual thereto, electrical conductors permanently extending between each said switch and its associated sound reproducing element, an electrically actuated sound producing element, a pick-up device thereat for converting said sounds into corresponding electrical oscillations, and means responsive to operation of any of said switches for actuating said sound producing element and for transmitting the corresponding electrical oscillations from said pick-up device to the reproducing element associated with said switch.

CHARLES AUTH.
